UNITED STATES PATENT OFFICE.

MIKEL J. QUINLIVAN, OF TORRANCE, CALIFORNIA.

VALVE SEAT AND LINER PULLER.

Application filed June 30, 1924. Serial No. 723,076.

This invention has to do with devices for pulling valve seats and cylinder liners from pumps.

While not in any way limited in application to a particular type of pump, the invention may be used with especial advantage in connection with the withdrawal of valve seats and cylinder liners of "mud hog" pumps employed for circulating mud-laden fluid through drill stems or casings during the sinking of oil or artesian wells. The abrasive effect of the grit in the mud rapidly wears away valve seats and cylinder liners, their useful life thus becoming so short that frequent replacement is necessary. The seats and liners are in the nature of cylindrical tubes or bushings, and they are necessarily pressed to seat very firmly. Consequently, it is a matter of great difficulty to remove them for replacement, especially in view of the fact that they offer no easily accessible gripping surfaces or shoulders to take pulling tools.

In the absence of auxiliary pumps, drilling and casing setting operations must necessarily cease while a circulating pump is being refitted with valve seats or liners, the time thus consumed representing a real factor in the ultimate cost of the well being drilled. Even though the use of auxiliary pumps eliminates the necessity of a "shut down" each time a pump is refitted, still, liner replacement operations, as accomplished by usual methods, are most expensive both from the standpoint of time consumed and from the fact that damage is often done to the pump casing bores in attempting to remove refractory liners.

Therefore, it is among the objects of my invention to provide a device whereby valve seats and cylinder liners may be positively and quickly withdrawn, irrespective of how firmly they may be seated; a device which is of utmost simplicity, being very cheaply manufactured and requiring but little skill to operate it; a device, which, in its application to work, will not harm the pump casing; and a device of sturdy construction whereby it is able to stand up under the severe service conditions to which it is exposed.

The puller will be fully described in the following detailed specification wherein further features of novelty and objects of the invention will also be set forth. References

will be had to the accompanying drawings, in which:

Fig. 1 is a medial section through the casting of a "mud hog" pump showing my improved puller in operative position thereon; 60

Fig. 2 is a fragmentary section on line 2-2 of Fig. 1;

Fig. 3 is a fragmentary side elevation of Fig. 1, as viewed from the right thereof, and showing the puller applied to the cylinder liner; 65

Fig. 4 is a section on line 4-4 of Fig. 1;

Fig. 5 is a perspective of a bearing block which may make up a part of my device;

Fig. 6 is a perspective of one of the pull rods of the device; and

Fig. 7 is a perspective of the rod supporting plate of the puller.

In Fig. 1 I have illustrated the "water end" of a "mud hog" pump; the pump casting being indicated at 10, the cylinder bore at 11, the cylinder liner at 12, and the valve seats at 13 and 14. Normally, the casing opening 15 (which is in axial alignment with cylinder bore 11,) and casing openings 16 and 17 (which are in axial alignment with seats 13 and 14, respectively) are closed by caps or heads (not shown) which are removable in order to give access to said valve seats and liners. 75 80 85

In order to conserve space, I have illustrated three pulling devices, A, B, and C, applied to the pump shown in Fig. 1, although it will be understood that ordinarily only a single puller will be applied to a given pump at any one time. Since the three pullers illustrated in this figure are of identical construction (except that the puller applied to liner 12 is provided with an auxiliary bearing block and with extra long pulling rods) they may be considered as illustrating a single device, and similar numerals of reference will be applied to such parts as are identical. In order that Fig. 1 may completely illustrate the construction 100 of the puller, the device B, shown applied to valve seat 14, is positioned at 90° with relation to device A, said device B being viewed in cross section as taken on line b—b of device A. 105

Generally, my device includes a bearing block adapted to span the valve or cylinder mouth, a cross plate disposed over the block, pull rods extending from the plate to the member to be pulled, and a wedge member 110

introduced between the block and plate to spread them apart and thus set up longitudinal, pulling movement of the rods. Obviously, inclined faces may be provided on either or both sides of the wedge member, and accordingly on either or both the bearing block and plate, to secure the described spreading movement, but, for purpose of illustrating the invention, I have shown the 10 wedges as having a single inclined face adapted to engage an inclined face on the bearing block, only. However, this specific showing is not to be construed as in any way limiting the invention, considered in its 15 broader aspects.

In Fig. 5 I have illustrated a bearing block 18 having an inclined wedge face 19 and rod positioning shoulders 20 (see Fig. 2), the block being adapted to bridge opening 16 (or 17) with the lower faces of its ends 21 bearing on the pump casing at opposite sides of the opening. In order that the block may be positioned properly with respect to openings 16 or 17 and may not 25 shift laterally over the pump casing, I provide a centrally arranged, depending portion 22 adapted to fit within openings 16 or 17, diametrically opposite positioning shoulders 23 formed by said portion being adapted 30 to engage the defining walls of said openings.

A wedge 24 is adapted to engage block face 19; and a cross-plate 25 is laid across wedge 24, the bifurcated ends 26 of said 35 plate being adapted to extend beyond the sides of the wedge and bearing block.

Pull rods 27, received within the bifurcations of plate 25, have heads 28, the under faces of which provide shoulders 29 40 adapted to bear on top plate 25 and thus serving to suspend the rods from the plate; while the lower ends of the rods have hooks 30 adapted to engage the inner ends of seats 13 or 14.

Preferably, angles 31 and 32 (Fig. 1) 45 are complementary to bring the upper faces of plate 25 and casing 10 into parallelism and so rods 27, with their right angle shoulders 29 in full engagement with plate 25, hang perpendicularly from said plate.

In certain situations, I may find it desirable to dispense with block 18 and to allow the wedge to coact directly with the upper face of casing 10 at each side the casing openings, but it will be understood that such an omission does not place the structure without the scope of certain of the appended claims.

With the device assembled as shown in 60 Fig. 1, it will be noted that hooks 30 extend beneath the inner ends 30^a of the valve seats, it being understood that rods 27 may be shifted through the bifurcations of plate 25 towards or away from the wedge and bearing block to take valve seats of different

diameters. Said bifurcations also allow the rods to be tilted so their lower ends may be moved towards one another while the puller is being assembled and moved to operative position.

Thereupon, wedge 24 is hammered home 70 between plate 25 and block 18 with the result that plate 25 is wedged upwardly, carrying with it rods 27 and hence freeing bushing 13 or 14 from their seats. It is obvious that the tremendous pulling power 75 exerted by the wedge is ample to withdraw the bushings even though they may have been very firmly pressed to seat, and that the withdrawal operation may be accomplished 80 without injuring any part of the pump.

In order that a single wedge block may be used either for pulling valve seats or cylinder liners (it being understood that cylinder liners are usually of greater diameter than valve seats, and that opening 15 is consequently larger than openings 16 or 17) I may provide an auxiliary bearing block 33 when the puller is to be applied to liner 12. Also, it will usually be necessary 85 to utilize pull rods 27^a of greater length than rods 27, when working upon cylinder liners. Block 33 is in the nature of a ring 34 held in spaced relation with casing 10 by legs 35, which latter may be removably 90 secured to said casing by bolts 36 threaded into the apertures provided for the usual head or cap bolts (not shown). The aperture 37 receives portion 22 of block 18 to prevent said block from shifting laterally 95 over the auxiliary block, while clearance 38 is provided to allow the passage of rods 27^a through the aperture without interfering with ring 35. It will be noted that rods 27^a are moved outwardly towards the ends 100 of plate 25 in order to fit the puller to the large diameter liner 12.

Auxiliary block 33 may also be used as a spacer in a situation where the outer or exposed end of the bushing, to be withdrawn, comes flush, or nearly flush with the pump casing. In such a situation, direct application of block 18 to casing 10 would close off the mouth of the withdrawal opening and prevent movement of the bushings 110 (whether they be valve seats or cylinder liners) while the insertion of block 33 so spaces block 18 from the mouth of the casing opening that relative movement between 115 casing and bushing is allowed.

It will be understood that various changes in design, structure and arrangement may be made without departing from the spirit and scope of my invention, and therefore, I do not wish to be limited to the drawings 125 and description set forth above except for such limitations as a fair interpretation of the appended claims may import.

Having described a preferred form of my invention, I claim:

1. In a device of the character described, a movable wedge member, a bearing block adapted to engage one side of the wedge, a cross-plate adapted to engage the opposite 5 side of the wedge, oppositely facing and individually movable hooks arranged at opposite sides of and spaced from the block, and means arranged at opposite sides of the block and individually connecting the hooks 10 and plate whereby separative movement of the block and plate caused by movement of the wedge moves said hooks with relation to said block.

2. In a device of the character described, 15 a movable wedge member, a bearing block adapted to engage one side of the wedge, a cross-plate adapted to engage the opposite side of the wedge, and a plurality of pull rods, each rod having a head at one end and 20 a hook at the other end, the headed ends of the rods being adapted to removably engage the plate whereby, when the plate and heads are in operative engagement, separative movement between the block and plate 25 caused by movement of the wedge imparts longitudinal movement to said rods.

3. In a device of the character described, a movable wedge member, a bearing block adapted to engage one side of the wedge, a 30 cross-plate adapted to engage the opposite side of the wedge, hooks spaced from the block, and adjustable means connecting the hooks and plate whereby separative movement of the blocks and plate caused by movement of the wedge moves said hooks with relation to said blocks.

4. In a device of the character described, a bearing block, a slotted cross plate, a movable wedge between the block and plate, and 40 pull rods extending, with clearance, through the slots in said plate and having heads adapted to engage said plate in a manner whereby separative movement between the blocks and plate caused by movement of the 45 wedge imparts longitudinal movement to said rods.

5. In a device for pulling a bushing from a pump bore, pull rods adapted to extend through the bore of said bushing and having hooks adapted to engage the inner end 50 of the bushing, a cross plate adapted to connect the ends of said rods, and a movable wedge adapted to coact with the pump casting and said plate in a manner whereby 55 movement of the wedge moves the plate away from the casing, and thereby moves

the pull rods longitudinally and draws the hooks and bushing towards the mouth of the pump bore.

6. In a device for pulling a bushing from 60 a pump bore, pull rods adapted to extend through the bore of said bushing and having hooks adapted to engage the inner end of the bushing, a bearing block adapted to bridge the mouth of the pump bore, a cross 65 plate adapted to connect the ends of said rods at a point beyond the block, and a movable wedge adapted to be driven between said bearing block and said plate.

7. In a device for pulling a bushing from 70 a pump bore, pull rods adapted to extend through the bore of said bushing and having hooks adapted to engage the inner end of the bushing, a bearing block adapted to bridge the mouth of the pump bore, positioning 75 shoulders on the block adapted to engage the pump casing to hold the block against shifting laterally across said mouth, a cross plate adapted to connect the ends of said rods at a point beyond the block, and a movable 80 wedge adapted to be driven between said bearing block and said plate.

8. In a device for pulling a bushing from 85 a pump bore, pull rods adapted to extend through the bore of said bushing and having 90 hooks adapted to engage the inner end of the bushing, a cross plate adjustably connecting the ends of said rods, and a movable wedge adapted to coact with the pump casting and said plate in a manner whereby 95 movement of the wedge moves the plate away from the casing and thereby moves the pull rods longitudinally and draws the hooks and bushing towards the mouth of pump bore.

9. In a device for pulling a bushing from 100 a pump bore, a bearing block adapted to bridge the mouth of the pump bore, pull rods extending at both ends beyond the block, one end of each rod being adapted to 105 extend through the bushing bore and having means adapted to engage the inner end of the bushing, a wedge bearing at one side on top of the block, a slotted cross plate on the opposite side of the wedge, the opposite extremity of each rod extending through a slot in the plate and having a head adapted to engage the top of the plate.

In witness that I claim the foregoing I have hereunto subscribed my name this 23rd day of June, 1924.

MIKEL J. QUINLIVAN.
